UNITED STATES PATENT OFFICE

FRANCES M. McCLURE, OF NEW YORK, N. Y., ASSIGNOR TO THE STATTON FURNITURE MANUFACTURING COMPANY, OF HAGERSTOWN, MARYLAND, A CORPORATION OF MARYLAND

DESIGN FOR A COMBINED DRESSER AND MIRROR

Application filed January 24, 1933. Serial No. 46,948. Term of patent 3½ years.

To all whom it may concern:

Be it known that I, FRANCES M. McCLURE, a citizen of the United States, residing at New York, in the county of New York and State of New York, have invented a new, original, and ornamental Design for a Combined Dresser and Mirror, of which the following is a specification, reference being had to the accompanying drawing, forming part thereof.

The figure is a perspective view of a combined dresser and mirror, showing my new design, the dotted lines showing conventional means for connecting the dresser and mirror.

I claim:

The ornamental design for a combined dresser and mirror, as shown and described.

FRANCES M. McCLURE.
